UNITED STATES PATENT OFFICE.

FERDINAND STRAUSS, OF NEW YORK, N. Y.

MECHANICAL TOY.

Application filed April 21, 1923. Serial No. 633,574.

To all whom it may concern:

Be it known that I, FERDINAND STRAUSS, a citizen of the United States of America, residing at New York city, county and State 5 of New York, have invented certain new and useful Improvements in Mechanical Toys, of which the following is a specification.

This invention relates to toys and in particular to the self-propelled type which emit 10 body an interest arousing feature which is also operated by the propelling means.

An object of the invention is to provide a movable toy having figures thereon which are operated to simulate a life-like motion, 15 the figures being operable alternately and continuously from the mechanism which propels the toy.

A further object of the invention is to provide a toy comprising a live stock car in 20 which chickens are being transported, some of which have escaped and are feeding on the roof of the car, they being operated by the mechanism to give a life-like appearance to their feeding movements.

25 Referring to the drawing in which one embodiment of my invention is illustrated; Fig. 1 is a view in side elevation of my improved toy, the operating mechanism being shown for driving the same and operating 30 the figures thereon;

Fig. 2 is a bottom plan view of the toy as seen in Fig. 1; and

Fig. 3 is a perspective view of the figure operating levers and the means for moving 35 the same.

Referring to the drawings in detail, 5 denotes a box car having sides and ends 6 and 7 respectively, between the former of which extend the axles 8 carrying wheels 9 40 which freely revolve and upon which the car travels. The ends of the axles 8 are journaled in extensions 10 of the sides 6 of the car, these extensions being painted to represent the journal boxes of freight cars.

45 A driving axle 8^a mounted as are the axles 8 is offset as at 12 and provided on one end with a pinion 13 with which engages a driving gear 14 formed on one end of a spring drum 15 which is carried on a shaft 16 50 journaled in the sides of the car. On this shaft, at the opposite end of the spring drum 15 is loosely mounted a ratchet wheel 17 to which one end of the spring 18, which encompasses the spring drum 15, is attached.

55 The other end of the spring is secured to the driving gear 14. A suitable pawl 19 is

pivotedly secured to the side of the car and in position to prevent any unwinding movement of the pawl. Two shafts 20 and 21 each carrying meshing gears 22 and pinions 23 are journaled in the sides of the car adjacent the spring drum, one of the pinions 23 meshing with the driving gear 14. This arrangement acts as a drag and slows the mechanism so that the wheels 24 can propel 65 the car.

Pivoted to one side of the car body as at 25 is a vertical lever 26, the lower end of which is offset and slotted as at 27 to receive the offset portion 12 of driving axle 8^a. 70 When the latter revolves it causes a throw of the upper end of the lever 26. The upper end of this lever has passed therethrough loosely a rod 28 which is pivoted to the top 75 29 of the car at the center thereof through the medium of a loose pin 30. The rod 28 also passes through two spaced bars 30^a to which are pivoted as at 31 the figure supporting extensions 32, which are pivoted also in the top of the car as at 33. The 80 figures 34 of the chickens may be shown as small and large and are operated alternately to peck into a wooden bowl 35 of feed between them on the roof of the car, so that on one end of the car one chick will be down 85 while the other is up and the diagonally opposite chicks on the opposite side of the bowl will be respectively up and down.

These movements will, of course, be caused by the alternate reciprocation of the bars 90 30^a through the action of lever 26, the latter of which will operate while the car is being propelled.

Thus I have provided a toy which while moving will be operating figures carried 95 thereby to provide an attraction which is life-like and amusing to children.

What I claim is:

1. A toy comprising a wheeled vehicle having a body portion, a top for said body portion, figures pivoted in said top, extensions on said figures, parallel bars carried in said extensions, a rod passing transversely through said bars for operating the same, said rod being pivoted in said top between 100 said bars, means for propelling said vehicle, comprising a driven axle, a lever extending between said axle and said rod, and means on said axle for operating said lever whereby movement is imparted to said figures. 105

2. A toy comprising a frame made to represent a railroad car, figures pivoted on the 110

top of said car, means for propelling said car, comprising a driven axle, bars to which said figures are connected, a rod passing transversely through said bars and being pivoted in the top of the car, at a point between said bars, a lever having one end associated with the axle and the other end with the rod and being adapted to operate the rod whereby a movement is imparted to said bars to cause simultaneous pivotal movement of said figures.

3. A toy comprising a frame made to represent a railroad car, figures pivotally asso-

ciated with the top of said frame, a driving mechanism for propelling said toy, said mechanism comprising a driven axle, a plurality of horizontally disposed parallel bars in said frame and to which said figures are connected, a pivoted rod passing transversely through said bars, and a pivoted lever connecting said driven axle and said rod whereby when the toy is being propelled, said figures are caused to have a life-like movement.

FERDINAND STRAUSS.
